UNITED STATES PATENT OFFICE.

BARNET SHAPIRO, OF BROOKLYN, NEW YORK.

DESIGN FOR LACE.

Application filed June 4, 1923. Serial No. 6,379. Term of patent 7 years.

To all whom it may concern:

Be it known that I, BARNET SHAPIRO, a citizen of the United States, and a resident of the city of New York (Sea Gate), borough of Brooklyn, in the county of Kings and State of New York, have invented a new and Improved Design for Lace, of which the following is a full, clear, and exact description.

The figure illustrates a piece of lace embodying my design.

I claim:

The ornamental design for lace, as shown.
BARNET SHAPIRO.
